DESIGN FOR A NIGHTGOWN

Samuel L. Freedgood, Long Beach, N. Y.

Application August 5, 1938, Serial No. 79,133

Term of patent 3½ years

To all whom it may concern:

Be it known that I, Samuel L. Freedgood, a citizen of the United States of America, residing in Long Beach, county of Nassau, and State of New York, have invented a new, original, and ornamental Design for a Nightgown, of which the following is a specification, reference being had to the accompanying drawing, forming part thereof.

Fig. 1 is a front view of a nightgown showing my new design.

Fig. 2 is a rear view thereof.

I claim:

The ornamental design for a nightgown, substantially as shown.

SAMUEL L. FREEDGOOD.
